UNITED STATES PATENT OFFICE.

FREDERICK E. KEY, OF ST. LOUIS, MISSOURI.

BOILER PLUG.

Application filed March 21, 1918. Serial No. 223,858.

To all whom it may concern:

Be it known that I, FREDERICK E. KEY, a citizen of the United States of America, a resident of the city of St. Louis, State of Missouri, have invented certain new and useful Improvements in Boiler Plugs, of which the following is a full, clear, and exact description, reference being had to the accompanying drawings, forming a part of this specification.

My invention relates to improvements in boiler plugs, one of the objects being to produce a strong and simple plug for closing openings in steam boilers and the like.

Another object is to produce a highly efficient leak-proof plug including a flexible packing member, and having its elements so constructed and arranged that the packing will be firmly forced onto its seat by the fluid pressure in the boiler, instead of by a screw or the like.

A further object is to provide a plug of this kind adapted to be easily and quickly applied to and removed from a boiler. Another object is to furnish a plug capable of being applied and removed an indefinite number of times without materially impairing the efficiency of its packing.

An important object is to provide an efficient boiler plug that can be easily applied and secured from the exterior of the boiler. Under some conditions, for example, in making tests required of some types of water legs, all of the elements of the plugs must be inserted through the openings to be closed thereby, and such plugs must withstand a very high degree of hydrostatic pressure. When so used, the plugs are only temporary closures for the openings. They are removed when the test is completed. Actual tests have clearly shown that the new plug, applied entirely from the outside of the boiler, will withstand a pressure much greater than 700 pounds per square inch. A very tight joint is produced by the fluid pressure forcing the packing onto its seat, and such pressure does not mutilate or otherwise materially injure the packing.

Specifically stated, an object of the invention is to produce a single device consisting of a combination of elements from which all of the foregoing advantages are obtained.

Fig. I is a vertical section of a portion of the water leg of a boiler, showing two of my plugs properly applied thereto, and also illustrating the manner in which the plugs

can be applied and anchored from the exterior of the boiler.

Fig. II is an enlarged vertical section illustrating the details of a plug constructed in accordance with my invention.

Fig. III is an inside view of the plug shown in Fig. II.

The water leg shown in Fig. I is provided with walls 1, each having plug-receiving openings 3. To illustrate a preferred form of the invention, I have shown a plug consisting of an inside anchor A, a tension member B secured to and extending outwardly from said inside anchor, and a closure consisting of a packing holder C and packing D secured thereto. The inside anchor A is in the form of a bridge, longer than the diameter of the opening to be closed, but narrow enough (Fig. III) to pass through said opening. When the plug is applied, as shown in Fig. II, the ends of this bridge A are seated against the inner face of the wall 1.

The tension member B is preferably in the form of a screw having a head 4 which engages the outer face of the packing holder C, and also having a threaded portion fitted to corresponding threads in the bridge or inside anchor A. By connecting the parts in this manner, I enable the inside and outside elements to be adjusted toward and away from each other. The inside anchor A can be adjusted away from the packing and packing holder, as shown at the upper portion of Fig. I, and while the parts occupy these relative positions, the inside anchor can be very easily and quickly inserted through the opening in the water leg of the boiler. The manner of inserting the inside anchor is suggested by the position of the plug at the upper portion of Fig. I.

After the ends of the inside anchor A have been seated on the inner face of the wall 1, the screw B can be easily rotated from the exterior of the boiler so as to advance the packing holder toward the anchor. For reasons which will be hereinafter pointed out, it is not necessary to use a wrench or other tool in tightening the plug. The screw head 4 can be turned by hand until the packing holder C engages the outer face of the wall 1, and the packing will be tightened automatically by the outward pressure of the fluid in the boiler.

The closure includes the packing holder C in the form of a cup having an annular flange 5 turned toward the inside anchor A

and adapted to seat against the outer face of the wall 1. The internal diameter of the annular flange 5 conforms approximately to the diameter of the opening to be closed, so 5 there is no abrupt offset or shoulder between the wall of the opening and the inner face of said annular flange. The packing D is preferably made of flexible material, such, for example, as leather or rubber. It con- 10 forms approximately to the shape of the cup-shaped packing holder C, and it is seated on the inner face of said holder. The packing may be secured to the holder by means of a clamping disk 6 surrounding the 15 screw B and contacting with the inner margin of the packing; and a clamping nut 7 mounted on the screw so as to retain the disk 6 in firm engagement with the packing. It is important to note that the packing 20 has a free, flexible, expansible annular flange 8 which extends from the annular flange 5 to engage the circular wall of the opening 3. This free, flexible, expansible annular flange is exposed directly to the out- 25 ward pressure of the fluid in the boiler, so that the fluid pressure will force said free flange into firm engagement with its annular seats, and at the same time place the screw B under tension. The packing is thus 30 automatically forced into firm engagement with its seats, a very tight joint being obtained by the pressure of the fluid on the packing, instead of, by tightening the screw B. 35 Since the inside diameter of the annular flange 5 conforms approximately to the internal diameter of the plug-receiving opening, there is no abrupt corner to cut or otherwise mutilate the packing when the 40 latter is firmly seated by the fluid pressure. The elements of the plug are so constructed and arranged that the flexible packing is merely placed under compression and forced onto smooth seats to form a seal between the 45 annular flange 5 and the outer face of the wall 1. The plug can therefore be applied and removed an indefinite number of times without materially impairing the efficiency of the packing. 50 Although made of flexible material, the packing is backed, or reinforced, by the metal packing holder C. The outward pressure of the fluid in the boiler, acting upon the packing and packing holder, places 55 the screw B under tension, and all of these elements are securely held by the inside anchor A. The plug is thus firmly secured

to the boiler, but it can be easily removed by merely turning the screw B and thereafter withdrawing the anchor, as suggested by the 60 upper portion of Fig. I.

I claim:—

1. A boiler plug comprising an inside anchor adapted to engage the inner face of the boiler wall to which the plug is applied, a 65 tension member secured to and extending outwardly from said inside anchor, and a closure comprising a packing holder secured to said tension member and adapted to engage the outer face of the boiler wall, and 70 a freely yieldable packing ring having an annular outer marginal portion secured to said packing holder and a free, flexible annular inner marginal portion conforming to 75 and adapted to be seated against the wall of the opening to be closed, said packing ring being exposed to receive the outward pressure of the fluid, so that the fluid pressure will force said annular marginal portions into engagement with their seats and 80 at the same time place the anchored tension member under tension.

2. A boiler plug comprising an inside anchor adapted to engage the inner face of the boiler wall to which the plug is applied, 85 said inside anchor consisting of a bridge longer than the diameter of the opening to be closed but small enough to be wholly inserted through said opening, a tension member secured to and extending outwardly 90 from said inside anchor, and a closure secured by said inside anchor, said closure including a packing holder in the form of a cup having an annular flange turned toward 95 said inside anchor, and adapted to engage the outer face of the boiler wall, the internal diameter of said annular flange conforming approximately to the diameter of said opening, and a packing ring arranged within 100 said cup and provided with a free, flexible annular packing flange engaging the inner face of the first mentioned flange and the wall of said opening, said packing ring also having an annular packing flange engaging 105 the inside face of said cup, said annular packing flanges being exposed to receive the outward pressure of the fluid, so that the fluid pressure will force said annular packing flanges into engagement with their annular seats and at the same time place the 110 anchored tension member under tension.

In testimony that I claim the foregoing I hereunto affix my signature.

FREDERICK E. KEY.
